UNITED STATES PATENT OFFICE.

RUDOLPH E. FREY AND JOHN BUSCHER, OF ST. LOUIS, MISSOURI, ASSIGNEES
OF ONE-THIRD TO GUSTAVE FREY, OF SAME PLACE.

BOOK-BINDING.

SPECIFICATION forming part of Letters Patent No. 397,848, dated February 12, 1889.

Application filed July 23, 1888. Serial No. 280,768. (No model.)

To all whom it may concern:

Be it known that we, RUDOLPH E. FREY and JOHN BUSCHER, both of the city of St. Louis, in the State of Missouri, have invented 5 a certain new and useful Improvement in Book-Binding, of which the following is a full, clear, and exact description, reference being had to the accompanying drawings, forming part of this specification, and in 10 which—

Figure I is a perspective view of a book embodying our invention. Fig. II is a perspective view of the facing. Fig. III is a detail perspective view showing part of the 15 sewing-band in the position it assumes when applied to the book, and showing also a cluster or bunch of the leaves. Fig. IV is a detail longitudinal section showing the manner of stitching the leaves to the sewing-band.

20 Our invention relates to an improvement in binding, the object being to re-enforce the means which facilitate the opening of the book, so that the leaves will open out flat at their inner edges, the invention being particularly applicable to such as account-books, 25 ledgers, &c.

Our invention consists in the feature of novelty hereinafter fully described, and pointed out in the claim.

30 Referring to the drawings, 1 represents the cover of the book, 2 the leaves, and 3 the facing. The facing is attached to the cover in any well-known or usual manner, and between the respective sides of the cover it is 35 made corrugated, as shown in Fig. III. Our

preferred method of making it is to take a piece, 4, (see Fig. II,) of suitable fabric or leather and secure to it at suitable intervals between them a number of strips, 5, of pasteboard, leather, or other suitable material. 40

6 represents the spaces between the strips 5.

The strips are applied by means of some adhesive material, or may be attached by stitching. When they are attached, the sewing-band is applied to the cover in a corrugated form, or, in other words, by bending it upward at the joint 6, the spaces at 6 allowing the strips 5 to fold neatly against each other, as shown in Fig. I. When the sewing-band has been attached to the cover, or before, if desired, the leaves 2 are attached in bunches or clusters to the inner edges of the corrugations, as shown in Figs. I and III, by means of stitches, as shown in Fig. IV, or otherwise. The result of this construction is, that 45 when the book is opened out the leaves will open or spread out flat from their outer to their inner edges, thus presenting a smooth and even surface for writing upon. 50

What we claim, and desire to secure by Letters Patent, is—

A sewing-band for books having strips secured thereto at suitable intervals, forming folding-spaces, substantially as described.

RUDOLPH E. FREY.
JOHN BUSCHER.
